UNITED STATES PATENT OFFICE

2,318,496

WARM AIR FURNACE

Adam Kamber, Youngstown, Ohio

Application September 9, 1942, Serial No. 457,688

2 Claims. (Cl. 126—115)

This invention relates to a warm air furnace.

The principal object of this invention is the provision of a warm air furnace provided with a novel radiating section formed integrally therewith.

A further object of the invention is the provision of a warm air furnace having a radiator section formed integrally therewith and means associated with the said radiator section for conveniently removing the fly ash, soot and other products of combustion deposited therein.

A still further object of the invention is the provision of a warm air furnace wherein the degree of heat exchange is relatively high due to the formation of the radiator portion thereof.

The warm air furnace, the subject of this invention, has been designed to obtain the highest degree of heat transfer possible in that the fire chamber and radiating areas of the furnace are so constructed that the hot gases, the products of combustion, are directed on a horizontal plane through and around a series of baffles which, in connection with the furnace, form a combined fire chamber and radiating structure. The radiating area of the furnace structure comprises an area relatively greater than that heretofore employed in various radiator structures attached to or forming a part of the warm air furnaces. The formation of the relatively larger radiating structure in connection with the fire chamber structure is made possible through the novel provision of means for positively removing at frequently intervals, the fly ash and other deposited products of combustion which normally tend to fill up and thereby block the passageway through radiating structures particularly when used with coal as the fuel. The radiating structure of applicant's invention is of considerable area with respect to the size of the fire chamber due to the fact that by applicant's novel structure the deposited products of combustion may be removed therefrom thereby insuring the continuous effective operation of the radiating structure and insuring an open passageway for the gaseous products of combustion from the fire chamber to a flue.

With the foregoing and other objects in view, which will appear as the description proceeds, the invention resides in the combination and arrangement of parts and in the details of construction hereinafter described and claimed, it being understood that changes in the precise embodiment of the invention herein disclosed, can be made within the scope of what is claimed

without departing from the spirit of the invention.

The invention is illustrated in the accompanying drawing, wherein:

Figure 1 is a cross sectional view on line 1—1 of Figure 2 of a furnace structure formed in accordance with applicant's invention.

Figure 2 is a cross sectional elevation taken on line 2—2 of Figure 1.

By referring to the drawing and Figure 1 in particular, it will be observed that the device of the invention comprises a warm air furnace, the essential portion of which is a combined fire chamber indicated by the numeral 10 and a directly connecting radiating structure indicated generally by the numeral 11. The fire chamber is provided with conventional grates 12 and the radiating structure is provided with a series of hollow baffles 13.

By referring to Figure 2 of the drawing, it will be observed that an opening 14 is provided communicating with the fire chamber 10, which opening serves as a feed door and is preferably provided with a collar-like extension 15 and a conventional hinged fire door 16. The collar-like extension 15 is provided to conveniently space apart from the actual furnace structure 10 and 11 a double walled outer casing 17 which is provided in double wall formation so that suitable insulation may be positioned between and thereby confine the heat transferred to the area between the casing and the furnace structure to that locality which in the drawing is generally indicated by the numeral 18. The casing 17 extends upwardly beyond the uppermost portions of the furnace structure 10 and 11 and forms a heat dome from which a plurality of warm air conducting pipes 19 lead to desirable locations. It is understood that in accordance with the usual customary provision for providing for the entrance of cold air into the lowermost portions of the space 18, openings, not shown, are provided and may connect directly with the room in which the furnace is positioned or may be connected with other rooms by means of suitable connecting cold air returns.

The products of combustion originating in the fire chamber 10 of the furnace structure pass, as is best illustrated in Figure 2 of the drawing, through a vertically positioned grate-like structure 20 into the integrally associated radiating structure 11 and pass therethrough in a passageway 21 defined by the hollow baffle members 13. At the extreme opposite end of the radiating structure, with respect to the fire chamber 10,

the various products of combustion are directed through a flue pipe 22 which is preferably placed in communication with a suitable chimney or other comparable structure. As is best illustrated in Figure 1 of the drawing, the flue pipe connection 22 is located near the lowermost portion of the radiating structure 11 so as to insure the satisfactory transfer of most of the heat generated before the products of combustion leave the radiating structure 11. It is possible to locate the flue pipe connection 22 in this position due to novel means incorporated in the furnace structure for removing the fly ash and other deposited products of combustion which would otherwise tend to fill up and block the radiating structure 11 and the passageway 21 therethrough. The novel means for removing the fly ash comprises the formation of the lowermost or bottom section of the radiating structure 11 in the form of a movable hinged bottom member 23 which is pivoted to the radiating structure 11 by means of a pivot 24 which extends beyond the casing 17, and as illustrated in Figure 2 of the drawing, a handle is affixed to the outermost end of the pivot member 24 so that downward movement imparted to the handle results in moving the movable bottom member 23 of the radiating structure downwardly and thus permits accumulated ash or other deposits thereon to be directed thereby into an adjoining ash pit 26 which is located beneath the fire chamber 10. Suitable springs 27 are positioned about the pivot member 24 in a manner normally holding the entire hinged bottom member 23 upwardly against the bottoms of the hollow baffles 13. In Figure 1, the hinged bottom member 23 is also illustrated in dotted lines in its lowered position thereby providing for the automatic removal of fly ash and other deposited products of combustion.

It is obvious that the hinged bottom member 23 may be formed of any suitable material and that the location of its hinge member 24 may be varied all within the scope of this invention as may be the means employed for positioning it against the bottoms of the hollow baffles 13 where it forms a practical and efficient closure.

It will thus be seen that upon a fire being established in the fire chamber 10 of the furnace structure upon the grates 12 therein, the material being burned will be retained by means of the vertically positioned grate-like structure 20 which will, however, not interfere with the sideward travel of the gaseous products of combustion into the adjoining radiating structure 11 and their passageway therethrough by means of the passageway 21 defined by the hollow baffle members 13. In this connection, it will be noted that the hollow baffles 13 are provided with integrally formed bottom members while they are open at their tops so that they form pockets in the radiating structure.

The gaseous products of combustion carry with them the fly ash and other heavier products of combustion which are ordinarily deposited in the passageway 21 on the hinged bottom member 23

thereof. The gaseous products of combustion eventually leave the radiating structure 11 of the furnace unit by means of the flue pipe connection 22. The furnace structure thus provides a radiating structure in direct connection with the fire chamber 10 in that the complete travel of the gaseous products of combustion is sidewardly away from the fire chamber 10 and around the various hollow baffle members 13, the number of which may be obviously varied in accordance with the degree of heat transfer desired. The air in the space 18 surrounding the actual furnace structure is thus readily heated by the transfer of heat from the structure of the fire chamber 10 and the radiator structure 11, the pockets formed by the hollow baffles 13 greatly facilitating the heat transfer. The heated air is conveniently directed away from the furnace structure itself by means of conventional pipes 19 which may obviously lead to desirable locations. It will be observed that the deposited products of combustion are easily removed to the ash pit 26 from the radiator structure 11 by means of the tiltable bottom member 23.

25 The furnace structure is provided with the customary draft and check controls so that the combustion taking place therein may be adequately controlled. The ash pit 26 is provided with a door structure similar in all respects to that heretofore described in connection with the fire chamber 10.

Having thus described my invention, what I claim is:

1. A furnace structure comprising a rectangular heating structure, one end thereof adapted to form a fire box, grates positioned in the said fire box, a radiating section in communication with said fire box, vertical grates separating the said fire box from the said radiating section, a plurality of baffles positioned in the said radiating section to form a winding passageway therethrough for the products of combustion, a flue pipe in communication with the said radiating section, a removable bottom member for said radiator member, means for normally holding the said removable bottom member in closed position, and means for imparting movement to the said removable bottom member so as to move the same away from the said radiator structure.

2. In a warm air furnace, the combination of a fire box and a radiating structure, the said radiating structure comprising an integrally formed assembly of hollow baffles open at their tops forming a winding passageway through the said radiator, a top member covering and enclosing the said winding passageway, a bottom member movably positioned with respect to the said radiator and normally forming a bottom for the said winding passageway, means for holding the said bottom member in closed position, means for depressing the said bottom member to open the same, and means positioned between the radiating structure and the fire box for preventing burning fuel in the latter from entering the former.

ADAM KAMBER.
